UNITED STATES PATENT OFFICE

SAMUEL STORCH, OF BROOKLYN, NEW YORK, ASSIGNOR TO THE EMELOID CO., INC., OF ARLINGTON, NEW JERSEY

HYGIENIC MOUTHPIECE

Application filed February 16, 1929. Serial No. 340,595.

This invention relates broadly to the art of telephony, and the improvements are directed to a novel mouthpiece adapted to be associated with the usual telephone transmitter.

In its broadest sense the invention contemplates the provision of a hygienic mouthpiece adapted to be removably attached to the usual standard mouthpiece of the transmitting or sending portion of a telephone instrument, said improved mouthpiece being acoustically developed to permit the whispering of the message without affecting its receiving clarity.

Specifically, the invention resides in the production of an article of the above-mentioned character, which may be manufactured at an extremely low cost to assure its commercial success, and which will permit of its consignment as a discard after a short period of use, or after a single use.

An important object is to provide a mouthpiece which may be carried about one's person and attached to a public telephone during the conversation, thus preventing the contraction of a disease due to lodged germs frequently present in such public telephones.

Still another object of the invention is to produce an article of the above-mentioned character which may be fabricated from flexible material, such as celluloid, or the like, and on which may be printed advertising matter of various descriptions, its low cost permitting of its distribution as an advertising medium, and at the same time benefiting the user in that private telephone calls may be made in a modulated voice, and relieving the user from the anxiety of contracting diseases from usual germ-laden mouthpiece.

A still further object is to provide an additional novel element whereby my improved mouthpiece may be attached to the transmitting portion of the well-known type of French telephone, wherein the transmitting and receiving portions are combined as a unitary structure.

With these objects in view, together with others which will appear as the description proceeds, the invention resides in the novel formation, combination and arrangement of

parts, all as will be described more fully hereinafter, illustrated in the drawings, and particularly pointed out in the claims.

In said drawings:

Figure 1 is a front elevation of my improved 55 hygienic mouthpiece.

Fig. 2 is a central, vertical sectional view thereof and illustrating the front portion of the usual mouthpiece carrying my invention.

Fig. 3 is a rear elevation of the mouthpiece 60 removed from the telephone transmitter.

Fig. 4 is a sectional view like unto Fig. 2, but further showing in section, a novel form of element whereby said mouthpiece may be removably attached to the French type of 65 telephone instrument.

Fig. 5 is an elevation of said element; and

Fig. 6 is a side elevation thereof.

Referring now more in detail to the accompanying drawings, wherein like characters of 70 reference denote similar parts throughout the several views, let 10 indicate generally my improved hygienic mouthpiece, which comprises a body portion 11, somewhat bell-shaped and presenting side portions which 75 gracefully flare outwardly toward the open end of said article. The rear portion is provided with a web 12, suitably apertured, as shown at 13, to permit the passage of the sound waves, produced by the human voice, 80 to the vibrating part of the telephone instrument. The parts just described are formed as of one piece and may be pressed to this shape from a single piece of flexible material, such as celluloid, or the like, the rim adjacent 85 the relatively large mouth, or open end, being rolled to present a smooth surface, as shown at 14.

The means for removably attaching the article to the standard mouthpiece 15 includes a flanged portion 16, the marginal edge thereof being bent inwardly, as indicated at 17, to engage said mouthpiece 15, when the latter is inserted therebeneath. In the present example of the invention said flanged portion 16 is formed integrally with a web portion 18, having apertures 19, alined with the apertures 13 of said web portion 12, both of said web portions being affixed in a suitable manner, such as cementing for instance. It 100

will further be observed that the base of said flanged portion 16 is slightly depressed, as shown at 20, to snugly engage the rear of said body portion 11, and at the same time to furnish a resting place for the inner marginal portion of said mouthpiece 15. It will, of course, be understood that the flexibility of the material permits the necessary expansion during the insertion of said mouthpiece 15.

10 In view of the relatively large open end presented by the body portion 11, the mouth of the user may be placed very close thereto, thus permitting the carrying on of a telephone conversation in a low voice approximating a whisper. By way of suggestion it is proposed to inscribe the word "Whisper" on said web portion 12, as clearly shown in Fig. 1, and in order that the article may also serve as an advertising medium, the inner portion of said body portion 11 may have printed thereon certain advertising matter, as shown at 21 in said Fig. 1. The low cost of producing the article permits of its distribution gratis to customers of the advertiser, and further the cheapness of the same permits it to be discarded after a single use or when it may appear to have become lodged with germs. Obviously, the mouthpiece may be cleansed if desired and serve its purpose for long periods of time.

15 In the types of instruments wherein the transmitter and receiving portions are combined, as in the French instrument for instance, the slightly modified form of transmitter requires an attachment to secure my mouthpiece to the same. To this end I have developed the member 22, having a sleeve portion 23 adapted to be inserted in the opening of the transmitter portion 24, diagrammatically illustrated in Fig. 4. Said member 22 is further provided with a circumferential flange 25 adapted to be inserted beneath said flange 16, the inturned portion 17 abutting the marginal portion of said flange 25 and maintaining the said member as shown in Fig. 4. It will be understood that said flange 16 may be flexed to permit the insertion or removal of said member 22, as desired.

20 From the foregoing it is apparent that I have developed a mouthpiece which is sanitary and hygenic, in that its low cost of production permits of its disposal to the waste basket after an extremely limited use, and as pointed out hereinbefore said article may be used as an advertising medium. That its use may become universal is foreseen by the additional advantage of being able to carry on a telephone conversation in a whisper, thus assuring privacy for confidential communications.

25 While the present is a disclosure of the preferred embodiment of the invention, it is to be understood that the same is not limited thereto, as various changes in the minor details of construction, proportion and arrange-

ment of parts may be resorted to without departing from the spirit of the invention as defined in the appended claims.

I claim.

1. A mouthpiece comprising a bell-shaped body portion adapted to be printed with advertising matter, an integral apertured web portion arranged at the rear of said body portion and a flange having an inturned portion adapted to be flexed to permit the insertion or removal of the mouthpiece of a telephone instrument. 70

2. A mouthpiece comprising a bell-shaped body portion, an apertured web portion arranged at the rear thereof, another web portion affixed to the first-named web portion and having a series of apertures alined with the apertures in said web portion and a flange carried by said second-named web portion, said flange being depressed and presenting an inturned portion adapted to be flexed to permit the insertion or removal of the mouthpiece of a telephone instrument. 80

3. A mouthpiece comprising a bell-shaped body portion and a marginal flange arranged at the rear portion thereof, said flange being depressed and having an inturned portion to permit of attachment or removal of said mouthpiece to the standard mouthpiece of a telephone instrument. 85

4. A mouthpiece comprising a bell-shaped body portion adapted to be printed with advertising matter, an integral apertured web portion arranged at the rear of said body portion and a marginal flange associated with said web portion, said flange being depressed and having an inturned portion adapted to be flexed to permit the insertion or removal of the mouthpiece of a telephone instrument. 90

100 In testimony whereof I affix my signature. 105
SAMUEL STORCH.
